UNITED STATES PATENT OFFICE.

CHARLES H. FOSTER, OF ST. LOUIS, MISSOURI.

HOT-AIR REGISTER.

SPECIFICATION forming part of Letters Patent No. 790,625, dated May 23, 1905.

Application filed December 11, 1903. Serial No. 184,772.

To all whom it may concern:

Be it known that I, CHARLES H. FOSTER, a citizen of the United States, residing in the city of St. Louis, in the State of Missouri, 5 have invented a certain new and useful Hot-Air Register, of which the following is such a full, clear, and exact description as will enable any one skilled in the art to which it appertains to make and use the same, reference 10 being had to the accompanying drawings, forming part of this specification.

The object of my invention is to produce a register which will be very simple in construction, consisting of the fewest possible parts, 15 and at the same time will be neat in appearance, durable, and efficient.

My invention consists in part in the combination, with the fixed part of a register provided with a valve-opening, of a movable valve, 20 of resilient material, for said opening, said fixed and movable parts coöperating to maintain various relative positions through the resiliency of the valve.

My invention also consists in various other 25 novel features and details of construction, all of which are described in the following specification and pointed out in the claims affixed hereto.

In the accompanying drawings, which illustrate one form of register made in accordance 30 with my invention, Figure 1 is a front elevation. Fig. 2 is an enlarged isometric projection of a part of the register. Fig. 3 is a section on the line 3-3 of Fig. 1; and Fig. 4 is a 35 view similar to Fig. 3, but showing the valve in its open position.

Like marks of reference refer to similar parts in the several views of the drawings.

10 is the frame or border of the register, 40 which is provided with an outer flange 11 and an inner flange 12. The outer flange 11 is adapted to seat against the wall, and the inner flange 12 is adapted to form a lap-joint with the register-box or flue-pipe in the well-known 45 manner. Within the inner flange 12 is the valve-opening, in which is situated the grille or grating. The grille or grating consists of two integral sets of bars arranged at an angle 50 to each other and in different planes, as de- scribed and claimed in my prior patent, No.

773,068, of October 25, 1904. This grille, however, in place of being made separate from the border or frame, as in my prior application, is formed integral therewith. The grille consists of a series of vertical bars 14 and a 55 series of horizontal bars 15. The vertical bars 14 join the upper and lower sides of the frame or border 10 and are slightly curved, as shown in Figs. 3 and 4. The horizontal bars 15 terminate at the outside bars 14, so as 60 not to make contact with the sides of the frame or border. By this construction I am enabled to cast the grille and border integral without injury to the border. If, however, the bars 15 were not curved or the bars 14 extended 65 to the sides of the frame, this could not be done, because the grille, containing less metal than the border, would cool first, and when the border cooled and contracted the pressure of the bars would disrupt the border. In my 70 construction, however, the long bars 15 do not bear against the sides of the frame and the short bars, owing to their curved form, will give slightly to accommodate the shrinking of the frame without exerting sufficient resist- 75 ance to injure the frame. The central bar 14 terminates out of contact with the upper side of the frame, and adjacent to it is formed a short bar 16. Between this short bar 16 and the central bar 14 is formed a short bearing- 80 bar 17 for purposes hereinafter to be described. This bearing-bar 17 preferably has a rounded top, as shown in Figs. 3 and 4.

20 is the valve, which is formed of sheet- 85 steel or other resilient material. The upper edge 21 of the valve is reinforced, and the valve is carried in end supports 22 and sprung into a central notch 23 in the manner de- 90 scribed and claimed in my prior patent above referred to. The upper portion of the valve 95 20 is slightly curved, and the curved portion preferably terminates in a shoulder 24, and said shoulder is preferably so formed as to fit over one of the cross-bars 15, as best shown in Fig. 3. The part of the valve below the shoulder 24 is made straight, and the lower edge is turned over at 25 to further strengthen the valve. The valve 20 is provided with a square perforation 26, through which passes 100 the body portion 27 of the member for re-

taining the valve in position. Extending downwardly from this portion 27 is an arm 28, carrying a finger 29, which rests against the rear face of the valve, preferably directly above the shoulder 24. The upper and forward part of the body portion 27 is provided with a pair of wings 30, which rest against the front face of the valve. Extending upwardly from the front of the body portion 27 is a rounded portion 32, which bears against the cross-bar 17, hereinbefore described. Projecting from the rounded portion 32 is the operating-plate 33, by means of which the valve is opened and closed. The short arm 31 is also, preferably, provided with a detent 34, adapted to bear against the top bar 15 when the valve is in its closed position, as shown in Fig. 3. The resiliency of the material of the valve will force the rounded portion 32 against the bearing-bar 17, so that the valve will be held by friction in whatever position it is placed. The required amount of friction can be obtained by properly proportioning the various parts of the register. The easiest way in which to regulate the pressure between the parts 17 and 32 is to vary the length of the finger 29, leaving the remaining parts of the register in the same proportion. It will be evident that by lengthening the finger 29 greater pressure will be obtained between the parts 17 and 32, and by shortening the said finger less pressure will be obtained.

In operation the valve of my register is opened by forcing the operating-plate 33 downwardly. This can be most easily accomplished by placing the foot upon the said plate. In order to close the valve, the plate is drawn upwardly, which would be most easily accomplished by placing the toe of the shoe underneath the said plate and drawing up upon it. The detent 34 serves to hold the valve firmly in closed position, so that it will not drop open when the register is being handled—as, for instance, in packing or in placing the register in position in the wall of a building.

It will be seen that my register is very simple of construction and at the same time is reliable in operation and owing to the small number of parts and simplicity is not liable to get out of order.

Having fully described my invention, what I claim as new, and desire to secure by Letters Patent of the United States, is—

1. In a hot-air register, the combination with the fixed part of a register having a valve-opening, of a movable valve of resilient material in said opening and provided with a bearing, and means dependent on the flexure of said valve in a transverse direction for forcing said bearing into frictional contact with the fixed part of the register.

2. In a hot-air register, the combination with the fixed part of a register having a

valve-opening, of a movable resilient valve for said opening, and an independent member carried by said valve and forced into frictional contact with the fixed part by the resiliency of the valve to hold the latter in position. 70

3. In a hot-air register, the combination with the fixed part of a register having a valve-opening, of a pivoted resilient valve for said opening, and an independent member carried by said valve and forced into frictional contact with said fixed part by the resiliency of the valve to hold the latter in position. 75

4. In a hot-air register, the combination with the fixed part of a register having a valve-opening, of a movable resilient valve for said opening, and a member bearing against both the front and rear of said valve, said member being forced into frictional contact with the fixed part of the register by the resiliency of said valve. 80

5. In a hot-air register, the combination with the fixed part of a register, having a valve-opening, of a movable valve of resilient material for said opening, and a member passing through said valve and bearing against both the front and rear thereof, said member being forced into frictional contact with the fixed part of the register by the resilience of said valve. 85 90

6. In a hot-air register, the combination with the fixed part of a register having a valve-opening, of a pivoted valve of resilient material for said opening, and a member bearing against both the front and rear of said valve, said member being forced into frictional contact with the fixed part of the register by the resilience of said valve. 95

7. In a hot-air register, the combination with the fixed part of a register having a valve-opening, of a pivoted resilient valve for said opening, and a member passing through said valve and bearing against both the front and rear thereof, said member being forced into frictional contact with the fixed part of the register by the resilience of said valve. 100 105

8. In a hot-air register, the combination with the fixed part of a register having a valve-opening, of a valve of resilient material pivoted in said opening and provided with a perforation, a member passing through the perforation in said valve, said member bearing upon the back of the valve below said perforation and on the front of the valve at or above said perforation, and a bearing carried by said member, said bearing being forced into frictional contact with the fixed part of the register by the flexure of said valve in a transverse direction. 110 115

9. In a new article of manufacture, a border for hot-air registers or the like, having a grille consisting of two sets of bars arranged at an angle to each other and formed integral with said border, one of said sets of bars terminating out of contact with said border. 120 125 130

10. As a new article of manufacture, a border for hot-air registers or the like, having a grille consisting of two sets of bars arranged at an angle to each other and formed integral with said border, one of said sets of bars being curved and the other of said sets of bars terminating out of contact with said border.

In testimony whereof I have hereunto set my hand and affixed my seal in the presence of the two subscribing witnesses.
